UNITED STATES PATENT OFFICE.

SERENO E. NORTON, OF EVANSTON, ILLINOIS.

STREET-SIGN POST AND HOLDER.

SPECIFICATION forming part of Letters Patent No. 659,314, dated October 9, 1900.

Application filed May 28, 1900. Serial No. 18,238. (No model.)

To all whom it may concern:

Be it known that I, SERENO E. NORTON, a citizen of the United States, residing in Evanston, in the county of Cook and State of Illinois, have invented a new and useful Improvement in Street-Sign Posts and Holders, of which the following is a specification.

My invention relates to sign posts and holders for street and other signs.

10 The object of my invention is to provide a sign post and holder for enameled-steel street-signs and other signs which will be of a neat appearance and of a simple, cheap, strong, durable, and efficient construction which 15 will securely hold the signs in position without the necessity of perforating the sign or breaking the enameling to insert screws, nails, or other fastenings through the sign, and will permit of expansion and contraction 20 under changes of temperature without injury to the sign or danger of bending or cracking the enamel. Heretofore enameled-steel street-signs have been secured to the sign post or holder by screws or other fastenings inserted 25 through holes made in the sign to receive them, thus breaking the enamel coating, and consequently leading to the speedy destruction of the sign by rusting of the metal, and thereby causing the enameling to chip or peel 30 off, as it will do when moisture and rust are permitted to attack the metal under the enamel coating where its continuity is once broken by cracks or holes or perforations through it, and where the enameled-steel sign 35 is secured rigidly by screws passing through it the enamel coating is frequently cracked or the sign injured by unequal expansion and contraction of the parts.

My invention consists in the novel construction of parts, and in the novel combinations of parts and devices herein shown and described, and specified in the claims.

In the accompanying drawings, Figure 1 is a side elevation of a street-sign post and holder 45 embodying my invention. Fig. 2 is an enlarged top or plan view. Fig. 3 is a perspective view of one of the metal brackets or sign-holders.

In the drawings, A represents a metal post- 50 pipe, preferably about two inches in diameter and nine and one-half or ten feet in length and provided at its bottom with a metal disk

B, preferably about six inches in diameter and having a hub or socket b to receive the lower end of the metal post-pipe A, to which 55 it is secured by a pin b', driven into suitable holes formed in the pipe and hub for this purpose. The bottom disk B of the post is further provided with two lateral flanges or wings b² to prevent the post turning in the 60 ground. C is a metal bracing-cup, preferably about six inches in diameter and four inches deep and provided with a hub or socket c, through which the pipe A loosely extends, so that the bracing-cup C may be lifted by the 65 frost without lifting the post A and its bottom disk B from or in the ground. This construction and combination of parts is of great practical utility where the sign-posts are planted in moist soil, such as clay or loam, 70 or where there is a tendency of the frost to lift the posts out of the ground. Though the post-pipe A fits loosely in the bracing-cup C, so that the one may slip or telescope in respect to the other, the bracing-cup, in connection with the bottom disk B, effectually 75 braces and stiffens the post-pipe in the ground. The bracing-cup C of the post is buried in the ground to a sufficient depth to cause it to be properly held in position and 80 to properly coöperate with the bottom disk in holding the post as a whole rigidly in its erect position.

The post-pipe A is provided at its top with a metal head or cap D, having a socket d to 85 receive the upper end of the post-pipe A, and to which it is rigidly secured by a metal pin d' driven into suitable holes in the pipe and cap. The metal cap D is provided with lateral sockets d² to receive the metal arms or 90 pipes E of the holder, which are preferably four in number, one extending to each of the corners or meeting angles of the signs. The arms E are preferably made in separate pieces from the head or cap D, and of gas-piping 95 about seven-eighths of an inch in exterior diameter. The outer ends of the arms E are provided with skeleton sign-holders F, each at the corner of two meeting signs and extending across the angle thereof, each of 100 which is provided with a socket f to receive the end of the arm E, and hook-shaped sockets or recesses f' f² extending at an angle to each other to receive the upper edges of two

signs G G, and with similar sockets $f^3 f^4$ arranged at an angle to each other to receive the bottom edges of the signs, and with similar sockets $f^5 f^6$ to receive the end edges of the signs. The skeleton holder F is preferably made of sheet-steel or other sheet metal and comprises a top piece F', a bottom piece F², and the two connecting-pieces F³ F³. The top and bottom pieces F' F² are of similar shape and each is provided with angular folds, bends, or flanges $f^7 f^8$ to form the sockets to receive the side edges of the sign. The intermediate or connecting pieces F³ F³ are similar in shape and each is provided with a 15 semicircular bend f^9 to form the socket f, with flanges f^{10} to form shoulders to fit against the top and bottom plates or pieces F' F², and with tongues f^{11} , which pass through slots f^{12} in the top and bottom pieces F' F² to secure 20 the top and bottom pieces to the connecting pieces by bending, clenching, or riveting the tongues. Each of the connecting or intermediate pieces F³ is provided with a wing f^{13} , which is furnished with bends or flanges f^{14} 25 f^{15} to form the socket f^5 or f^6 , which receives the end edge of the sheet. The post-pipe A, its cap or head D, and arms E are all galvanized, the galvanizing being preferably done after the post-pipe A, its cap or head D, and 30 the arms E are all put together, so that these parts will be securely united by the galvanizing, or, in other words, thus be galvanized together. The top plate F' of the holder F is secured to the other parts of the holder after 35 the signs G are put in place. The signs being slipped edgewise into the sockets $f^3 f^4 f^5 f^6$ of the holders, the top plates F' are then applied so that the sockets $f^3 f^4$ embrace the upper edges of the signs, and then the tongues 40 f^{11} , which are inserted through the slots in the top plate F', are bent or clenched down, thus firmly uniting the top plate F' to the connecting-pieces F³ F³ of the holder. In this way it will be seen that the enameled- 45 steel or other decorated signs are firmly supported and secured in place without cracking the enamel or making any screw-holes or perforations through the signs, and that while the signs are firmly supported in the 50 sockets of the holders they are at the same time not screwed rigidly at any point to the holder, so that there is no danger of injury to the signs or to the enamel or other decorative coating of the same by reason of expansion and contraction under changes of temperature.

By reason of the skeleton form of the sign-holders F and the fact that the arms E extend to the corners of the signs and that the 55 holders simply extend across the angle formed by two signs, near the corner thereof, the sign-holders add little weight to the top of the post and do not materially tend to make it top-heavy, while at the same time the signs, post, and holders, as an entirety, are given a very neat and strong and substantial appearance, and the holders and arms are be-

hind the signs and concealed from view and offer little surface for the collection of snow or ice and do not obstruct the view of the signs.

As illustrated in the drawings, my sign post and holder is provided with four arms E and four sign-holders F and is adapted to hold or support in position four signs G, the signs being arranged at right angles to each other and the sockets to receive the signs on each holder standing, of course, at the same angle to each other. The sockets, however, may be arranged at any angle required to each other 80 and the device adapted to receive and support three, four, five, or any other number of signs required. For example, to receive and support three signs I would provide the device with three arms E and three holders 85 F, and the sockets $f^3 f^4$ thereon would be arranged at sixty degrees to each other instead of at an angle of ninety degrees, as shown in the drawings, where four signs are employed. The signs G are made of sheet-steel and 90 enameled, the enamel coating protecting the metal from rust.

I claim—

1. The sign post and holder, comprising in combination the post-pipe A, the bottom disk 95 B secured thereto, a bracing-cup C having a socket through which the post-pipe passes, a cap or head D secured to the top of the post-pipe and provided with a number of holder-arms E and sign-holders F on the outer ends 100 of said arms E, and each provided with hook-shaped sockets or recesses $f^3 f^4$ arranged at an angle to each other to receive the top edges of the signs, and similar sockets $f^5 f^6$ to receive the bottom edges of the signs, and similar sockets $f^5 f^6$ to receive the end edges of the signs, substantially as specified.

2. The combination with signs arranged at an angle to each other and a skeleton sign-post, of arms therefor extending to the corners or meeting angles of the signs, and sign-holders secured to said arms at the ends thereof and each extending across the corner or angle formed by two meeting signs, and provided each with sockets to receive the upper 115 and lower edges and end edges of the signs, substantially as specified.

3. The combination with signs arranged at an angle to each other and a skeleton sign-post and its arms extending to the corners or meeting angles of the signs, of sign-holders on the ends of the arms and each extending across the corner or angle formed by two meeting signs, and having top and bottom pieces each provided with sockets at an angle 125 to each other to receive the top and bottom edges of signs extending at an angle to each other, substantially as specified.

4. The combination with signs arranged at an angle to each other and a skeleton sign-post and its arms extending to the corners or meeting angles of the signs, of sign-holders on the ends of the arms and each extending across the corner or angle formed by

- two meeting signs, and having top and bottom pieces each provided with sockets at an angle to each other to receive the top and bottom edges of signs extending at an angle to each other and having also intermediate connecting-pieces provided with sockets to receive the end edges of the signs, substantially as specified. 5
5. The combination with a sign-post and its arms, of sign-holders on the ends of the arms having top and bottom pieces each provided with sockets at an angle to each other to receive the top and bottom edges of signs extending at an angle to each other and having also intermediate connecting-pieces provided with sockets to receive the end edges of the signs, said connecting-pieces having tongues extending through slots in the top and bottom pieces, substantially as specified. 10
10. 6. The combination with a number of signs standing at an angle to each other, of holders at the meeting angles of the signs comprising each a sheet-metal top piece F' having angle bends or flanges forming sockets f' f², a sheet-metal bottom piece F² having angle bends or flanges forming sockets f³ f⁴ therein, and intermediate connecting-pieces F³ F³ having bends or flanges f¹⁴ f¹⁵, substantially as specified. 15
15. 7. The combination with signs arranged at an angle to each other, of holders at the meeting angles of the signs having top and bottom pieces, each furnished with sockets at angles to each other for receiving the top and bottom edges of the signs, and means for securing said top piece to the holder after the signs are in place in the bottom piece, substantially as specified. 20
20. 8. The combination with signs arranged at an angle to each other, of holders at the meeting edges of the signs having top and bottom pieces, each furnished with sockets at angles to each other for receiving the top and bottom edges of the signs, and means for securing said top piece to the holder after the signs are in place in the bottom piece, said means consisting of tongues passing through slots in said top piece, substantially as specified. 25
25. 9. The combination with a sign-post having arms, of sign-holders on the ends of the arms, having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, said connecting-pieces F³ F³ having wings f¹³ furnished with sockets f⁵ f⁶ to receive the end edges of the signs, substantially as specified. 30
30. 10. The combination with a sign-post having arms, of sign-holders on the ends of the arms having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, said connecting-pieces F³ F³ having tongues f¹¹ passing through slots in said top and bottom pieces, substantially as specified. 35
35. 11. The combination with a sign-post having arms, of sign-holders on the ends of the arms, having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, said connecting-pieces F³ F³ having tongues f¹¹ passing through slots in said top and bottom pieces, substantially as specified. 40
40. 12. The combination with a sign-post having arms, of sign-holders on the ends of the arms, having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, said connecting-pieces F³ F³ having wings f¹³ furnished with sockets f⁵ f⁶ to receive the end edges of the signs, and said connecting-pieces F³ F³ having tongues f¹¹ passing through slots in said top and bottom pieces, substantially as specified. 45
45. 13. The combination with post-pipe A having cap or head D furnished with sockets d to receive the post-pipe, and sockets d' to receive arms, arms E, signs G, sign-holders F having each a top piece F', furnished with bends or flanges f⁷ f⁸ forming sockets or recesses f' f², bottom pieces F² having bends or flanges f⁷ f⁸ forming sockets f³ f⁴, connecting-pieces F³ F³ having semicircular bends f⁹ forming sockets f to receive the ends of said arms E, flanges f¹⁰ to form shoulders to fit against the top and bottom pieces F' F², and tongues f¹¹ passing through slots in said top and bottom pieces, said connecting-pieces F³ F³ having also each a wing f¹³ provided with bends or flanges f¹⁴ f¹⁵ forming sockets for the ends of the signs, substantially as specified. 50
50. 14. The combination with a sign-post having arms, of sign-holders on the ends of the arms having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, substantially as specified. 55
55. 15. The combination with a sign-post having arms, of sign-holders on the ends of the arms having top piece F' furnished with sockets f' f² at an angle to each other to receive the top edges of the signs, and a bottom piece F² furnished with sockets f³ f⁴ at an angle to each other to receive the bottom edges of the signs, and intermediate connecting-pieces F³ F³ having sockets f to receive the end of the post-arm, substantially as specified. 60
